UNITED STATES PATENT OFFICE

2,623,277

COMBINED HAIR COMB AND CUTTER

Walter S. Lefebre, Haverford, Pa.

Application May 5, 1949, Serial No. 91,621

1 Claim. (Cl. 30—30)

1

My present invention comprises a combined hair comb and cutter.

It has been recognized that a combined hair comb and cutter which is capable of being used by all persons for their own use would serve a definite need. Such a combined comb and cutter could be used in dressing the hair, in cutting the hair, in trimming it, and in general in greatly reducing the frequency with which professional barbers or hair dressers need be visited.

While I am aware that others have already suggested various forms of combined hair combs and cutters, the devices of this character known to me are subject to certain disadvantages. In the first place, even the most successful devices are somewhat complicated in construction and consequently expensive. Other known devices are undesirable because they are actually dangerous to the user, particularly when removing or inserting a blade therein.

An object of my present invention is to overcome the disadvantages of the prior devices known to me and to provide a device which is simple in construction, easy to use and clean, which has the cutting blade at an angle to the surface being cut, and which permits of the cutting unit to be slid along the comb so as to enable trimming of the hair at any relative position of the comb and cutter, even close to the ear, as well as easy cutting on both the fine and coarse teeth.

In accordance with my present invention wherein I provide a device which will be simple and inexpensive to manufacture and use, sturdy and durable in construction, reliable in operation and attractive in appearance, I attain the foregoing and other objects by utilizing ordinary stock combs having back and teeth portions, a cutting blade, and a special novel clip of my invention.

My novel clip comprises a lower portion which is flat, an upper portion having a leading edge, two projections extending forwardly from each end of the leading edge of said upper portion and which projections cover the ends of the cutting edge of the blade when the latter is in cutting position, a lug on the under side of the upper portion, the lug being of a size and configuration suitable to permit it to engage with the opening or openings in the blade when the blade is placed against the lug and the clip carrying the blade is placed around the comb in cutting relation. Joining the upper and lower portions of my novel clip is an arcuate portion adapted to fit snugly around the back of the comb and to press upon the teeth on both sides near the comb's back.

2

With the foregoing in mind, my present invention consists of certain novel features of construction and combinations and arrangement of parts which will be more fully hereinafter described and which will become apparent from the following detailed description taken in connection with the accompanying drawings in which like characters represent like parts throughout and which form a part hereof.

19 In the drawings:

Fig. 1 is a side elevation of a preferred embodiment of my novel hair comb and cutter;

Fig. 2 is similar to Fig. 1 except that it is a rear view of the device shown in Fig. 1;

15 Fig. 3 is a front plan view of the novel hair comb and cutter of Fig. 1, the teeth being omitted;

Fig. 4 is a section taken along the line 4—4 of Fig. 1;

20 Fig. 5 is a cross-section taken along the line 5—5 of Fig. 1;

Fig. 6 is a cross-section taken along the line 6—6 of Fig. 2;

25 Fig. 7 is a front side elevation of my novel clip, with its upper portion nearest the viewer;

Fig. 8 is a front open end view of the clip shown in Fig. 7;

30 Fig. 9 is a section taken along the line 9—9 of Fig. 8 and shows a single edge blade in place on my novel clip;

Fig. 10 is a side elevation of a single edge blade which may be used in accordance with my present invention;

Fig. 11 is similar to Fig. 9 but shows also the 35 lower portion on my novel clip nearest the viewer;

Fig. 12 is a side elevation of a double edge blade which may be utilized in accordance with my present invention;

Fig. 13 is a cross-section taken along the line 40 13—13 of Fig. 12;

Fig. 14 is similar to Fig. 6 but shows an embodiment of my novel clip wherein the lug is stamped from the upper portion of the clip;

45 Fig. 15 is similar to Fig. 5 but shows a modification of my novel clip wherein the upper portion thereof may be hingeably attached to the arcuate portion of the clip; and

Fig. 16 is a fragmentary view of one end of a stock comb modified to permit of easy trimming therewith in accordance with my invention.

Referring to the drawings, a stock comb 1 has back 2 and fine and coarse teeth, 3 and 4, respectively. The teeth of the comb have tips 5.

50 My novel clip 6 comprises an upper portion 7, a lower portion 8, and an arcuate portion 9 joining the upper and lower parts. The leading

edge 10 of the upper portion 7 is at a greater distance from the tips 5 of the teeth than is the cutting edge 12 of the blade 11 utilized in accordance with my invention. The upper portion 7 also has projections 13 extending forwardly from each end of the leading edges of the upper portion 7 of my clip. These projections 13 cover the ends of the cutting edge 12 of the blade 11 when the blade is in cutting relation on the comb 1. The under side of the upper portion has a lug 14 secured thereto. This lug 14 is of a size and configuration to render it suitable for engagement with the opening 15 of the blade 11. If desired, the lug 14 may be stamped from the upper portion of the clip 6 and in effect be a stamped out part 16 thereof.

If desired, instead of my novel clip 6 being a unitary structure it may comprise more than one integrated piece. For example, in Fig. 15, a modified clip is shown wherein the upper portion 7 is attached to the arcuate portion 9 by hinges 17 and is provided with spring means 18 to hold the upper portion against the teeth in normal position.

The operation of my novel device is simple. A blade 11, either a single or a double edge blade having at least one opening 15 therein, is placed against the under side of the upper portion 7 of my novel clip 6 so as to permit the lug 14 of my clip 6 to engage the opening 15 of the blade 11, the blade of course being placed on my clip 6 in such a way that the cutting edge 12 of the blade is close to the leading edge 10 of the upper portion 7 of my clip 6. My novel clip 6, together with the blade 11 associated therewith, may then be placed around a regular comb 1, for example, by sliding the clip 6 over the comb 1 so that the arcuate portion 9 passes around the back 2 of the comb 1, preferably beginning with the fine teeth end of the comb.

As may be seen from Fig. 1 the clip 6 may be placed in any position along the length of the comb 1. If the clip 6 is in the position shown in solid lines in Fig. 1, in other words in approximately the center of the comb, part of the blade 11 or razor will be over the fine teeth C and part of the razor over the coarse teeth A. If the clip 6 is in the position generally indicated by Y in Fig. 1 it will be over the fine teeth C. Similarly, if the clip 6 is in position Z it will be over the coarse teeth D. In any of these or other positions the clip 6 firmly holds the blade 11 in place against the comb 1 by reason of the snug fit of the clip around the comb, the engagement of the blade 11 with the lug 14 on the under side of the upper portion 7 of the clip 6 and the two projections 13 which extend forwardly and preferably downwardly against the blade 11. While, however, the clip 6 firmly holds the blade 11 in place for cutting and combing purposes, a special advantage of my novel clip is the easy altering of its position on the comb to any desired place. It is not necessary to turn any dial or unscrew any screws in order to attain a change of position, which is the case in some of the prior art structures. All that need be done is to push the clip to the desired position.

Another advantage of my novel clip and comb combination is the fact that the cutting edge 12 of the blade 11 is always at an angle to the tips of the teeth, as the lengths of the fine teeth and coarse teeth are not the same, making for a non-circular back portion, and as is well known this is an aid in the cutting of hair. Still another advantage of my novel comb and clip combination is that, if desired, my device may be employed to trim hair close to and around the ear. If this is desired, one or both of the end teeth 19 of the comb may be thinner than is normally the case with regular stock combs as shown in Fig. 16. A further advantage of my combined comb and cutter is the ease with which any hair which may clog the teeth can be removed from the device. This is in contra-distinction to other devices with which I am familiar. In such devices it is cumbersome and in some cases dangerous to remove the hair which clogs the teeth.

Furthermore, while my invention has been described in detail as to construction and arrangement of parts it is understood that some modifications may be made herein without departing from the spirit of my invention. In view of the foregoing no limitations are intended other than those imposed by the scope of the appended claim construed as broadly as permissible in view of the prior art.

I claim:

A clip adapted to hold a blade having at least one opening therein in cutting relation on a comb having a back portion and teeth in front thereof, said clip having a lower portion, an upper portion having a leading edge which is at a greater distance from the front of the teeth than is the cutting edge of the blade, projections extending forwardly from each end of the leading edge of said upper portion and covering the ends of the cutting edge of the blade, an elongated lug on the under side of said upper portion, said lug being of a size suitable to enable the lug to engage said blade when the latter is placed against the under side of the upper portion, and an arcuate portion joining the sides of said upper and lower portions.

WALTER S. LEFEBRE.
